(57) **CLAIM**

The ornamental design for a cutting tool, as shown and described.

DESCRIPTION

FIG. 1 is a perspective view of a cutting tool showing a first embodiment of our new design;

FIG. 2 is a top plan view of the cutting tool of FIG. 1;

FIG. 3 is a bottom plan view of the cutting tool of FIG. 1;

FIG. 4 is a right side elevational view of the cutting tool of FIG. 1;

FIG. 5 is a left side elevational view of the cutting tool of FIG. 1;

FIG. 6 is a front elevational view of the cutting tool of FIG. 1;

FIG. 7 is a rear elevational view of the cutting tool of FIG. 1;

FIG. 8 is a perspective view of a cutting tool showing an alternative embodiment of our new design;

FIG. 9 is a top plan view of the cutting tool of FIG. 8;

FIG. 10 is a bottom plan view of the cutting tool of FIG. 8;

FIG. 11 is a right side elevational view of the cutting tool of FIG. 8;

FIG. 12 is a left side elevational view of the cutting tool of FIG. 8;

FIG. 13 is a front elevational view of the cutting tool of FIG. 8; and,

FIG. 14 is a rear elevational view of the cutting tool of FIG. 8.

The broken lines depict portions of the hand-held cutting tool in which the design is embodied that are not considered part of the claimed design.

1 Claim, 10 Drawing Sheets
